CLAIM

The ornamental design for a shooting stick blind, as shown and described.

DESCRIPTION

FIG. 1 is a perspective view of a shooting stick blind incorporating my new design;

FIG. 2 is a perspective view of an opposite side thereof;

FIG. 3 is a front elevation view thereof;

FIG. 4 is a rear elevation view thereof;

FIG. 5 is a left side view thereof;

FIG. 6 is a top plan view thereof; and,

FIG. 7 is a bottom plan view thereof.

The broken lines showing blind sleeves in FIGS. 2 and 4, and a clamp in FIGS. 1-5 are included for the purpose of showing environmental portions of the shooting stick blind and forms no part of the claimed design.
